UNITED STATES PATENT OFFICE.

RICHARD H. WORCESTER, OF HONOLULU, AND GEORGE DUNCAN, OF OLA, TERRITORY OF HAWAII.

STAKE SOCKET.

Application filed March 1, 1927. Serial No. 171,886.

This invention relates to stake sockets for use at the sides of trucks, flat cars, etc. and is particularly directed to a socket embodying a stake releasing door.

For heavy service duty it is desirable to have a stake socket from which the stake may be released without pulling it vertically therefrom as is the method in the common socket. For this reason a release door is provided on the face of the socket so that the stake can be removed laterally from the socket, this being a much simpler and easier method especially when there is a heavy lateral load thrust against the stake, binding it in the socket.

In this type of socket the side walls are subject to breakage, since the front does not integrally bind the sides together against the spreading action imparted by the stake under load. Then too, it is necessary that the door be quickly and easily releasable when the load wedges the stake in the socket thereby causing the stake to bear heavily against the door and also that the door may be positively held shut when the socket is in service.

It is therefore an object of this invention to provide in a stake socket of the releasing door type, a swinging latch bar adapted to engage over the face of the door, the end of the latch bar engageable into the frame so as to be frictionally held and the bar to be positively held across the face of the door against accidental displacement, the engagement of the bar end with the frame springing the bar slightly to aid frictional engagement across the door face.

Another object is to provide a latch bar of this nature for use in conjunction with a hinged door, the latch pivoted to the socket and adapted to spring over a lug on the face of the door at the time that the bar end is set within the frame, the releasing being accomplished by exerting a slight lateral pull on the handle to bring the bar back over the lug.

Another object is to provide reinforcing means on the inner face of the door adapted to engage one of the socket side walls to prevent spreading of the side walls, this engagement in conjunction with the hinged connection of the door, reinforcing and bracing the side walls of the socket when the door is closed and the socket is in service.

Still another object is to provide a socket door of this nature in which a latch bar is pivoted to the socket frame and adapted to be aligned with an opening in the door when

it is desired to release the door and to engage over the portions of the door at each side of the opening when the door is in service or closed position.

Further objects and advantages will be more fully set forth in the description of the accompanying drawings forming a part of this specification, in which:

Figure 1 is a front view of the socket showing it in service position.

Figure 2 is a plan view of the socket.

Figure 3 is a side view thereof more clearly illustrating the latching means for the door.

Figure 4 is a detailed sectional view taken on line 4-4, Figure 3, detailing the lugs on the door for reinforcing the socket side walls.

Figure 5 is a detailed sectional view taken on line 5-5, Figure 3, detailing the pivot for the latch bar.

Referring to the drawings, the socket comprises a frame 1 and a door 2 hinged to the frame. The socket frame is attached to the truck structure 3 by means of bolts 4 engaging the truck structure through flanges 5 at each side of the socket frame. Pairs of horizontally disposed side wall reinforcing ribs 6 are formed at each side of the socket frame and a flange 7 extends from the rear of the socket so as to overhang the top of the truck frame.

A square closure is formed by side walls 8 formed integral with and projecting out from the truck engaging portion 9 of the frame. The portion 9 forms the rear wall of the closure and the door 2 closes the face side thereof. A bottom 11 also integral with the socket frame sustains the stake 12 in the closure.

The door 2 is hinged to a frame side wall as at 13 in a conventional manner. A latching bar 14 for the door is pivotally attached to the opposite wall of the socket in such manner as to be swung vertically across the door face. Pivotal attachment for the bar is through a bolt 15 extending through a boss 16 formed on the socket side wall (see Figure 5). The boss 16 is situated toward the forward end of the side wall and extends out therefrom the thickness of the door 2, the door being slotted as at 17 so as to straddle the boss and also provide a release opening for the latch as described hereafter.

Immediately above the boss 16, a portion of the frame extends out and overhangs the upper edge of the closed door. A tapered

notch or slot 18 is formed on the lower side of the overhanging portion, the slot being disposed in the path of movement of the swinging upper end 19 of the latch bar. The 5 taper of the slot causes the bar end to be frictionally gripped upon insertion therein, the wide end of the slot being at the point of bar end entrance. Setting of the bar in locked position is further accomplished by 10 a slight disalignment of the slot from the path of movement of the bar end, movement of the bar end into the slot causing the bar to be sprung laterally, thereby more firmly maintaining it in the slot. The tapered slot 15 may be said to be just beyond the outer face of the door when the door is shut, this arrangement providing that the bar is in contact with the door across its entire face. The door is slightly thickened at the top thereof so as to cause it to bear against the latch when 20 the latch bar is sprung outward at its upper end. The door as shown may be of a ribbed structure, this, however, being immaterial except for purposes of manufacture and 25 weight.

The lock bar is further maintained in its locked position by virtue of its engagement with a lug 20 (see Figure 4) formed on the face of the door below the bar pivot. The lug 30 20 may be termed a "catch" since it functions to prevent accidental return or release movement of the bar from its engagement with the tapered slot. The bar strikes the inclined face 21 of the lug and snaps over the lug, 35 with easy return thereof prevented by means of the engagement of the bar with a second or more abruptly inclined surface 22 of the lug. The release of the door is accomplished by pulling outward on the lower end of the 40 bar and forcing it back over the lug, this movement of the bar disengaging it from the tapered slot, and further movement aligning the bar with the release opening in the door, this allowing the door to be swung unob- 45 structed past the then horizontally disposed latch bar.

Means for reinforcing the socket are provided on the door inner face for the purpose of preventing spreading of the socket side 50 walls when heavy pressures are imparted on the stake inserted in the socket. The reinforcement is in the form of lugs or projections 23 formed integral with the door at its latching end above and below the release 55 opening in the door. These projections are provided with flat inner faces positioned at right angles to the door inner face for engagement with the outer face of the side wall when the door is swung shut, the outer walls 60 being inclined to further strengthen the lugs. The two side walls of the socket may be said to be tied together by the door when the door is shut and the socket is in use, since the door has a hinged connection to one side 65 wall and the projections 23 overhang the

opposite side wall. This construction gives the stability required in a stake socket and further provides a convenient stake release without impairing the strength of the socket.

Having described our invention, we claim: 70

1. A socket of the class described, comprising, a socket frame open at the front, a hinged door adapted to close said front, the swinging end of said door provided with a slot, a latch bar pivoted to said frame at 75 a point in the path of the slot whereby the bar may be swung into engagement across the face of the door at the sides of the slot for locking the door, and the door releasable by aligning the bar with the slot. 80

2. A stake socket of the class described, comprising, a stake end closure frame open at one side, a door hinged to the frame for closing said open side, said door having a slot at the swinging end thereof, a latch bar pivoted to said frame at a point straddled 85 by the slotted door end and alignable with the slot, and said frame having a notch disposed in the path of swing of the end of the bar so as to frictionally hold the bar end when the bar is swung from alignment with the slot to locked position across the face of the door. 90

3. A stake socket of the class described, comprising, a socket frame open at one side, 95 a stake release door for closing said open side, and a latch bar mounted on the frame and adapted to engage across the width of the door outer face for locking the door in closed position. 100

4. In a device of the class described, a frame for receiving the end of a stake, said frame open at one side thereof for a lateral release of a stake inserted therein, a door hinged at said open side, a latch bar pivoted to said frame for engagement across the face of the door, a portion of said frame overhanging said door and having a notch therein disposed in the path of swing of the latch bar end, and a lug on the face of the door 105 adapted to engage the edge of said bar for preventing accidental return movement of the bar after its end has been set in said notch. 110

5. In a stake socket of the class described, 115 a socket frame having a laterally disposed opening therein, a hinged door adapted to close said lateral opening, and a latch bar attached to said frame and adapted to be swung across the face of the door, said bar end engageable with a portion of said frame 120 for frictionally holding the bar in locked position across the door. 125

6. In a stake socket of the class described, 130 a socket frame open at one side thereof, a hinged door adapted to close said open side, a latch bar pivotally attached to said frame and movable across the face of said door, said bar frictionally engageable with a portion of said frame, and a catch formed on

the face of said door for further maintaining the bar in position across the face of the door.

7. In a stake socket of the class described, 5 a socket frame having a lateral opening therein, a hinged door adapted to close said lateral opening, a latch bar pivotally attached to said frame and adapted to be swung across the door face, said door slotted at its latch 10 end and straddling said bar pivot when the door is closed, said frame having a tapered slot therein positioned in the path of swing

of said bar for frictional engagement by the bar end, and a lug on the door face ab-
stracting accidental return of the bar from 15 engagement with the slot, said lug present-
ing a gradually inclined face to the locking
movement of the bar, and a sharply inclined
face to prevent accidental return thereof.

In witness whereof, we hereunto subscribe 20
our names.

RICHARD H. WORCESTER.
GEO. DUNCAN.
